United States Patent

Des. 239,257
Patented Mar. 23, 1976

239,257

CONTAINER END

Alfred Edward Balocca, Wheaton; Paul Wilson Hardy, Barrington, and Karl Philip Hemeyer, and Harlen Edgar Wilkinson, Crystal Lake, Ill., assignors to American Can Company

Filed Mar. 18, 1974, Ser. No. 452,129

Term of patent 14 years

Int. Cl. D9—07

U.S. Cl. D9—253

FIG. 1

FIG. 2

FIG. 1 is a top plan view of a container end showing our new design;

FIG. 2 is an enlarged scale cross-sectional view taken along line 2—2 of FIG. 1.

We claim:

The ornamental design for a container end, substantially as shown and described.
